UNITED STATES PATENT OFFICE.

DANIEL V. ORTONA, OF DETROIT, MICHIGAN.

DESIGN FOR A HAIR-DRIER CASING.

Application filed October 11, 1928. Serial No. 28,456. Term of patent 7 years.

To all whom it may concern:

Be it known that I, DANIEL V. ORTONA, known as Dan Orton, a citizen of the United States, residing at Detroit, in the county of Wayne and State of Michigan, have invented a new, original, and ornamental Design for Hair-Drier Casing, of which the following is a specification, reference being had to the accompanying drawing, forming part thereof.

Fig. 1 is a side elevation and
Fig. 2 is a front elevation.

I claim:—

The ornamental design for a hair drier casing, as shown.

DANIEL V. ORTONA.
